DESIGN FOR A COMBINED HANDLE AND ESCUTCHEON

James C. Hermann, Los Angeles, Calif.

Application February 28, 1939, Serial No. 83,471

Term of patent 7 years

To all whom it may concern:

Be it known that I, James C. Hermann, a citizen of the United States, residing at Los Angeles, in the county of Los Angeles and State of California, have invented a new, original, and ornamental Design for a Combined Handle and Escutcheon, of which the following is a specification, reference being had to the accompanying drawing, forming a part thereof.

Fig. 1 is a side elevational view of a combined handle and escutcheon, showing my new design.

Fig. 2 is an end elevational view, and

Fig. 3 is a top plan view thereof.

I claim:

The ornamental design for a combined handle and escutcheon, as shown.

JAMES C. HERMANN.
